UNITED STATES PATENT OFFICE.

LESTER L. JONES, OF ORADELL, NEW JERSEY.

VARIABLE-AIR CONDENSER.

Application filed July 7, 1926. Serial No. 120,947.

This invention relates to variable air condensers, and has special reference to the provision of improvements in variable air condensers of the multiple or gang type.

- 5 As is well known, multiple variable air condensers are employed in radio circuits for effecting the simultaneous tuning of a plurality of associated circuits, such condensers being now commonly employed in
- 10 radio receiving circuits of the so-called tuned radio frequency type in which it is desired to simultaneously control the resonance or tuning of a plurality of cascaded circuits.
- 15 To effect the simultaneous adjustment or unicontrol of a plurality of tunable circuits, multiple condensers of various types have been suggested, among which the two most common forms are, first, the condenser construction in which the rotors are arranged coaxially and operated by a single shaft, and second, the type of condenser construction in which the condenser units are mounted side by side and are coupled together by
- 20 some mechanical means for effecting the simultaneous rotation of the rotor shafts.
- 25

One of the most difficult problems that has confronted the art in the design of these multiple condensers especially for sharply tunable radio receiving circuits is that of producing a resulting condenser construction in which the condenser units are matched with the precision or exactness required for producing simultaneous tuning of the circuits and particularly over the whole wave length range over which the radio receiving system is tunable. Numerous methods have been suggested or devised for solving this problem, such as the provision of independently adjustable plates connected in circuit with the condensers or small adjustable condensers connected in circuit with the tuning condensers etc.; but these, as far as I am aware, have not proved successful in practice. Numerous factors met with in the manufacture and assembly as well as in the continued use of the condensers vitiate the results obtainable with the use of these independently adjustable plates or condensers; and the problems confronting the worker in the art are found to increase with the number of condenser units which are desired to be joined for simultaneous operation. In spite of the suggested solutions, the most common way known in the art today of effecting the exact tuning

of the associated radio receiving circuits resides in producing independent adjustments of the condenser units for effecting the refined setting thereof after a coarse setting is obtained by a simultaneous adjustment.

A prime desideratum of my present invention resides in the design and construction of a multiple or gang condenser which may be manufactured and assembled especially by quantity production methods so that the condenser units are matched with that precision required for effecting the simultaneous tuning of sharply tuned radio receiving circuits, with the construction such that the condenser units and the assembled condenser construction remain stable after extended periods of service.

A still further principal object of my present invention relates to the provision of single condenser units embodying a number of the features or advantages of the multiple condenser construction.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiment of my invention, and in which:

Fig. 1 is a top plan view of a multiple condenser showing four units in gang arrangement and embodying the principles of my present invention.

Fig. 2 is a front elevational view thereof shown on an enlarged scale.

Fig. 3 is a cross-sectional view thereof taken in the plane of the line 3-3, Fig. 1.

Fig. 4 is a cross-sectional view thereof taken in the plane of the line 4-4, Fig. 1.

Fig. 5 is a longitudinal fragmentary cross-sectional view thereof taken in the plane of the line 5-5, Fig. 1.

Fig. 6 is a longitudinal cross-sectional view taken in the plane of the line 6-6, Fig. 5 and showing the same on a more enlarged scale.

Fig. 7 is an enlarged cross-sectional view of a compensating condenser employed with the multiple condenser taken in the plane of the line 7-7, Fig. 6, and

Fig. 8 is a view of the compensating condenser taken in cross-section in the plane of the line 8-8, Fig. 7.

Referring now more in detail to the drawings and having reference first to Fig. 1 thereof, my invention may be said to comprise in one of its generic aspects the provision of a multiple or gang condenser of the type in which the rotors are arranged coaxially, all operable from a common shaft and about a common axis, the condenser comprising a supporting frame structure F and a plurality of condenser units C', C², C³ and C⁴ mounted in the frame, each of the condenser units comprising a stator and a rotor designated respectively by s and r with an exponent corresponding to that of the condenser unit of which it forms a part.

To carry out the principles of my invention, I depart from the method now used of assembling the rotors and stators, which method consisted in connecting the rotors conductively on a common shaft and in insulating the stators of the independent condenser units from the frame and from each other; and in accordance with the principles of my invention, the stators s'-s⁴ each comprising a stator plate set having a number of condenser plates are mounted on the frame in conductive connection therewith, while the rotors r'-r⁴ each also comprising a rotor plate set having a plurality of plates arranged to interleave with the stator plates are mounted on the frame insulated therefrom and from each other. Although the rotor units are thus mounted in independent insulated condition, they are connected together so that the aligned rotor shafts thereof are connected for rotation in unison all operable by a single shaft. With this mode of assembly, as will become clearer hereinafter, each of the condenser units is in effect an independent condenser unit capable of independent adjustment and therefore capable of being connected to the other condenser units and built in gang or assembled relation without introducing the difficulties of support and adjustment which were found incident to multiple condensers built in accordance with the prior mode of assembly.

As a second step in the carrying out of my invention, each of the independently adjustable rotors is mounted on the supporting condenser frame in a manner to effectually take up the radial and axial strains, each of the rotor units being also so mounted as to permit of independent lateral and axial adjustments thereof, which adjustments are independent also for each rotor unit, permitting each of the condenser units to be set or adjusted in the assembling operation without affecting the adjustment of any other condenser unit, and permitting the building up of the assembled condensers in the manner specified.

To facilitate the understanding of the method of inter-relating the condenser units,

I will first describe the construction and mode of operation of one of the condenser units by reference particularly to Figs. 5 and 6 of the drawings in which the condenser unit C' and the manner of mounting the same on the frame F, as well as the manner of connecting the same to the condenser C², are shown on an enlarged scale.

The frame F comprises a plurality of longitudinal supporting rods, here four in number, 10, 11, 12 and 13 connected together at their front ends by the pedestal supports 15 and 16 by means of the screw bolts 17, 17 and similarly connected together at their rear ends (see Figs. 1, 3 and 4) by means of the pedestal supports 18 and 19. These longitudinal supporting rods are also joined together at intermediate points by a plurality of tie plates which form the bearing plates for the rotor units, as will be described hereinafter. The plates of the rotor plate sets s'-s⁴ are mounted in the longitudinal supporting rods 10 to 14, the rods being suitably milled to receive portions of the stator plates in the manner shown particularly in Figs. 3, 4 and 6 of the drawings. The stator plate sets are arranged alternately on opposite sides of the condenser assembly to produce a balanced construction, and to this end the stator plates of the stator units s' and s³ are fixed to the lower pair of supporting rods 12 and 13, while the stator plates of the units s² and s⁴ are fixed to the upper pair of longitudinal supporting rods 10 and 11, all as will be seen from a comparison of Figs. 1 and 3 and Figs. 1 and 4.

Referring now again particularly to Figs. 5 and 6 of the drawings, each of the rotor units such as the rotor unit r' comprises a shaft 20 carrying the plates of the rotor unit, which plates are fixed to the shaft in accordance with any well-known method, such shafts being milled, for example, to receive central portions of the plates in a manner shown particularly in Figs. 3 to 6 of the drawings. The shaft 20 is mounted for rotation in oppositely positioned bearings generally designated as b', b², the mounting being such that the shaft 20 is adjustable axially and also preferably laterally or radially with respect to said bearings. The means for mounting the rotor unit and the shaft thereof is, moreover, such that all radial and axial strains are taken up and so that the rotor unit may be insulated from the frame F and from the other rotor units by dielectrics presenting a maximum amount of strength in each direction with a minimum amount of material located in the dielectric field.

Each of the bearings such as b', b² is preferably made in accordance with the method disclosed in my copending application Ser. No. 111,073, filed May 22, 1926, so as to render the same entirely free from "shake" or

play, each of the said bearings comprising a shaft portion designated by 21 with an exponent corresponding to the bearing of which it is a part, the shaft portion being 5 provided with oppositely positioned steel cones designating as 22 fixed to the shaft portion and cooperating with corresponding cone ends of a bearing box 23 fixed to a pair of plates 24 and 25, which plates are joined 10 to the longitudinal supporting rods 10—13 and form tie plates as well as bearing supporting plates, these parts being indicated by the reference characters with exponents applied thereto corresponding to the bearings of which they form the parts. These tie plates 24 and 25 are received by suitable milled slots in the longitudinal supporting rods 10—13 and similarly receive the bearings such as b' and b^2 , as will be readily evident from a consideration of Figs. 3, 4 and 6 of the drawings.

Each of the rotor units such as the rotor r' is mounted in the bearings b and b^2 insulated therefrom, the mounting including 25 means for adjusting the rotor unit axially to adjust the space or clearance between the rotor and stator plates and radially or laterally to match the contours of said rotor and stator plates, this construction permitting the exact matching of the condenser units of the gang assembly. The rotor mounting means comprises rotor supporting members disposed laterally of the rotor and connecting the same to the bearing supports 30 at laterally spaced points combined with axially disposed rotor spacing members which are axially adjustable in the bearings for predetermining the spacing between the plates, this comprising more specifically a pair of insulating plates 26 and 27 (designated with an exponent corresponding to the condenser unit in which they form parts) made of sheet dielectric and joined to opposite ends of the rotor shaft, a pair of metallic plates 28 and 29 (with corresponding exponents) fixed to the ends of the bearing shaft portions such as 21' and 21², the said plates being connected together at points spaced laterally of said shafts, the construction including a pair of stud insulators 30 and 31 (designated with similar exponents) fixed to opposite ends of the rotor shaft and engaged by adjustable screw studs such as the studs 32' and 33' which are threadedly 45 adjustable in the shaft portions 21' and 21², the latter being suitably interiorly threaded to receive the said studs.

The insulating plates such as plates 26' and 27' are preferably fixed to the opposite 60 ends of the shaft 20 by riveting the shaft ends onto the plates and the conducting plates such as 28' and 29' are similarly fixed or attached to the bearing shafts by riveting the ends of the bearing shafts onto the said plates, all as clearly shown, for exam-

ple, in Figs. 5, 6 of the drawings. An insulating plate is connected to a conducting plate at the points spaced from the rotor shafts by means of studs 34, 34 suitably riveted to one of said plates, which studs 70 threadedly receive screw bolts 35, 35 engaging the other of said plates, all as clearly shown in Fig. 6 of the drawings. The apertures in the dielectric plates 26' and 27' which receive the screw bolts 35 are preferably made enlarged as at 36 (see Fig. 6), this being provided so that the rotor unit may be adjusted radially in any direction with respect to the bearings so as to match up the contours between the rotor plates and so the stator plates. By matching up the contours, it will be appreciated that each of the condenser units may be made to conform to a predetermined calibration curve, the radial adjustment taking care of the unavoidable 85 accumulated errors found in manufacturing and assembling the plates and supports for the condenser units. The stud insulators such as 30' and 31' preferably are made of quartz and engage the adjusting studs 32' 90 and 33' so that adjustment of the latter in the bearing shafts effects the axial spacing of the rotor plates.

By means of this construction it will be seen that the radial and axial strains of the 95 rotor are effectively taken up by the connecting plates and adjustable studs, the former defining the lateral or radial supporting means for the rotor and the latter defining the axial spacing and supporting 100 means therefor. It will be further seen that a maximum amount of supporting and operating strength is thus provided in both axial and radial directions with a minimum amount of insulating material, the sheet dielectric and stud insulators being, moreover, located in a dielectric field of low strength. It will be further seen that each side of the rotor may be independently adjusted in almost any direction producing a universal 110 and flexible mounting for the same, the radially arranged insulating material being axially flexible though radially rigid to effect the desired result. Moreover, it will be apparent that each rotor unit is rendered 115 independent of the other rotor units so that a similar flexible mounting is provided for each rotor and similar adjustments effected therefor.

The manner in which the condenser units forming the assembly are inter-related to produce the aforementioned results will now become more evident. The bearing b^2 arranged intermediate the condenser units C' and C² is a bearing common to two condenser units; and adjacent ends of adjacent rotor shafts are independently adjusted and supported in the common bearing. Thus the forward end of the rotor r' is mounted on the bearing b^2 by means of the plates 120

26² and 28² connected together by means of the studs 34 and stud bolts 35 similar to those heretofore described, the shaft of the rotor r^2 being provided with the insulating 5 stud 30² engaged by the screw stud 32² threadedly adjustable in the common bearing shaft 21², the said bearing shaft being also common to the supporting plates of the adjacent rotors r' and r^2 .

10 This method of interconnecting the rotor units may be carried out for any number of condenser units, the same being shown employed for four condenser units in Fig. 1 of the drawings; and referring now to 15 Fig. 1 of the drawings, it will be seen that the remaining condenser units are interconnected by bearings b^3 , b^4 and b^5 supported in bearing and tie plates 24 and 25 designated with exponents corresponding to the 20 bearings of which they form parts, the condenser rotors being mounted or hung on these bearings in a manner similar to that heretofore described by means which are designated by corresponding reference characters. 25

By means of this construction, all of the rotor units may be operated in unison by the rotation of the front projecting shaft portion 21', rotation of the condenser rotors 30 being limited to a semi-revolution by means of the stop elements generally designated as 37. It will be further seen that all of the stators are firmly supported in the condenser frame F and that each of the rotors 35 is flexibly mounted for independent adjustment, although all of the rotors are connected for operation in unison. The tie plates 24², 25² etc. arranged intermediate adjacent condenser units are conductively 40 integral with the condenser frame and therefore serve as a means for shielding one condenser unit from the others. The rotor supporting plates such as plates 29' and 28² also for similar reasons serve as shield 45 plates, and these are preferably made oval-shaped as clearly shown in Figs. 3 to 5 of the drawings, so as to embrace the whole sweep of the condenser plates to effectively shield one unit from the next, the oval shape 50 being desired also to more readily facilitate assembly of the shaft and attached plates into the stator frame. The line joining the studs 34 is at an acute angle to the major axis of an oval supporting plate so 55 as to permit easy assembly of the parts and particularly the attachment of the plates by the stud screws. Desirably the rear end of the assembly is provided with a plate 38 to which is attached a leg bracket 39.

60 With the above-recited construction I have found that the individual condenser units of the assembly may be readily matched to produce the same calibration curves and may be operated in circuit to 65 produce exact resonance in sharply tuned

circuits without necessitating the individual adjustments of the condenser units to obtain a fine or sharp adjustment. I have found, moreover, that the adjusted values remain stable in operation and in continued 70 service.

The axial and radial adjustments effected produce a condenser matching over the desired wave length range, and in order to effect an equalization of the minimum capacities of the condenser units when in connected circuit, I prefer to additionally provide compensating condensers which I will now describe. It will be understood that in connected circuit the capacities of the 75 leads, the electron discharge tube and coils vary for the different circuits; and I prefer to utilize the compensating condensers for equalizing at the minimum setting of the condensers these circuit capacities. 85

One of the compensating condensers is shown associated with the condenser units C and the same is shown particularly in Figs. 6 to 8 of the drawings. This compensating condenser comprises an insulating 90 sheet 40 forming a support for the condenser and fixed to the longitudinal supporting rods 11 and 12 positioned in milled slots 95 therein, the compensating condenser further including a high potential plate 41 held to the insulating support 40 by means of four ears 42, 42 turned over in corresponding notches in the insulating piece 40, the high potential plate having at one end a tab 45 to which the spring lead 46 of the rotor is soldered, said plate being further provided with a connecting end piece 46'. Between the high potential plate 41 and a conducting plate 47 also supported in the rods 11 and 12, there is provided a mica rectangle 48 approximately twenty mills thick which is slipped between the high potential plate 41 and the conducting plate 47, the latter being the ground plate. 100

The ground plate 47 is also supported in 110 the rods 11 and 12 by means of milled slots and the difference between the slots holding the plates 40 and 47 should be just sufficient to accommodate the plate 41 and the mica piece 48. Adjustment of the condenser is made first very roughly by the insertion of the mica rectangle and final adjustment is made by pulling together the plates 40 and 47 by means of a screw nut 49, the opening in the plate 41 surrounding the screw nut 115 being preferably enlarged as shown. After making this adjustment a touch of solder may be applied to the face of the nut 49. The dimensions of this compensator condenser are made preferably such that the same 120 may be adjusted between the values of 20 and 30 mmfds. 125

The manner of making and assembling the gang multiple condenser of my present invention and the many advantages thereof 130

will in the main be apparent from the above description thereof. It will be further apparent that a number of the advantages obtained in the building of multiple condensers are also characteristic of the making of single or unit condensers as shown, for example, in Fig. 6 of the drawings, and may be so utilized. It will be further appreciated that while I have shown and described my invention in the preferred form, many changes and modifications may be made in the structure described without departing from the spirit of the invention, defined in the following claims.

15 I claim:

1. In a variable air condenser, a stator plate set, a rotor plate set unit and a mounting means for rotatably supporting the rotor unit, said mounting means including mechanism for adjusting the rotor unit axially to fix the spacing or clearance between the rotor and stator plates and for adjusting the rotor unit radially to match the contours of the rotor and stator plates.

25 2. In a variable air condenser, a stator plate set, a rotor plate set unit and a mounting means for rotatably supporting the rotor unit, said mounting means including mechanism for adjusting the rotor unit axially to fix the spacing or clearance between the rotor and stator plates and mechanism for independently adjusting the rotor unit radially to match the contours of the rotor and stator plates.

35 3. In a variable air condenser, a frame, a stator plate set conductively mounted on said frame, a rotor plate set unit and a mounting means for insulatably supporting the rotor unit on said frame, said mounting means including mechanism for adjusting the rotor unit axially to fix the spacing or clearance between the rotor and stator plates and for adjusting the rotor unit radially to match the contours of the rotor and stator plates.

45 4. In a variable air condenser, a frame, a stator plate set conductively mounted on said frame, a rotor plate set unit and a mounting means for insulatably supporting the rotor unit on said frame, said mounting means including mechanism for adjusting the rotor unit axially to fix the spacing or clearance between the rotor and stator plates and mechanism for independently adjusting the rotor unit radially to match the contours of the rotor and stator plates.

55 5. In a variable air condenser, a frame, a stator plate set mounted on said frame, a rotor plate set unit, bearings on opposite ends of said frame and means rotatably mounting said rotor unit in said bearings, said means comprising members for axially adjusting the rotor unit relative to said bearings and members for radially adjusting the rotor unit relative to said bearings.

6. In a variable air condenser, a frame, a stator plate set mounted on said frame, a rotor plate set unit including a shaft, bearings in said frame, and means rotatably mounting said rotor unit in said bearings, 70 said means comprising rotor supporting members disposed laterally of said rotor shaft and connected to the bearings for supporting therein the rotor unit at laterally spaced points, and axially disposed rotor 75 spacing members axially adjustable in said bearings for axially spacing and supporting the rotor unit therein.

7. In a variable air condenser, a frame, a stator plate set mounted on said frame, 80 a rotor plate set unit including a shaft, bearings in said frame, and means rotatably mounting said rotor unit in said bearings, said means comprising axially flexible but radially rigid rotor supporting members 85 disposed laterally of said rotor shaft and connected to the bearings for supporting therein the rotor unit at laterally spaced points, and axially disposed rotor spacing members axially adjustable in said bearings 90 for axially spacing and supporting the rotor unit therein.

8. In a variable air condenser, a frame, a stator plate set mounted on said frame, a rotor plate set unit including a shaft, bearings in said frame, and means rotatably mounting said rotor unit in said bearings, said means comprising axially flexible but radially rigid rotor supporting insulating plate members disposed laterally of said rotor shaft and connected to the bearings for insulatably supporting therein the rotor unit at laterally spaced points, and stud insulators disposed axially of said rotor shaft and adjustably connected to said bearings 100 for insulatably adjustably spacing and supporting the rotor unit axially in said bearings.

9. In a variable air condenser, a frame, a stator plate set mounted on said frame, a rotor plate set unit including a shaft, bearings in said frame, and means rotatably mounting said rotor unit in said bearings, said means comprising members fixed to said bearings and shaft, extending laterally 110 therefrom and connected together at points spaced laterally of said shaft, certain of said members being axially flexible though radially rigid, and axially disposed members engaging the rotor shaft and adjustable in said 115 bearings for axially spacing and supporting the rotor unit therein.

10. In a variable air condenser, a frame, a stator plate set mounted on said frame, a rotor plate set unit including a shaft, fixed 125 bearings in said frame, and means rotatably mounting said rotor unit in said bearings, said means comprising members fixed to said bearings and shaft extending laterally therefrom and connected together at points spaced 130

- laterally of said shaft, certain of said members being laterally adjustable with respect to the others, and axially disposed stud members engaging the rotor shaft and threadedly adjustable in said bearings for axially spacing and supporting the rotor unit therein.
11. In a variable air condenser, a frame, a stator plate set mounted on said frame, a rotor plate set unit including a shaft, bearings in said frame, and means rotatably mounting said rotor unit in said bearings, said means comprising insulating plates fixed to said rotor shaft, conducting plates fixed to the bearing shafts, means connecting the plates together at points spaced laterally of said shafts, insulating studs fixed to the rotor shaft, and stud members engaging the insulating studs and threadedly adjustable in said bearing shafts.
12. A multiple variable air condenser comprising a supporting metallic frame, a plurality of stator plate sets mounted on said frame, and conductively connected thereto, a plurality of independent coaxially arranged rotor plate set units cooperating with the stator plate sets, and means connecting the axially alined shafts of all the rotor units for rotation in unison, said means including mechanism for mounting the rotor units insulated from each other and from said frame.
13. A multiple variable air condenser comprising a supporting metallic frame, a plurality of stator plate sets mounted on said frame and conductively connected thereto, a plurality of independent coaxially arranged rotor plate set units cooperating with the stator plate sets, means connecting the axially alined shafts of all the rotor units for rotation in unison, said means including mechanism for mounting the rotor units insulated from each other and from said frame, and means for adjusting a rotor unit relative to a stator plate set.
14. A multiple variable air condenser comprising a supporting metallic frame, a plurality of stator plate sets mounted on said frame and conductively connected thereto, a plurality of independent coaxially arranged rotor plate set units cooperating with the stator plate sets, means connecting the axially alined shafts of all the rotor units for rotation in unison, said means including mechanism for mounting the rotor units insulated from each other and from said frame, and means for independently adjusting each of the rotor units relative to its associated stator plate set.
15. A multiple variable air condenser comprising a supporting frame, a plurality of stator plate sets mounted on said frame, a plurality of independent coaxially arranged rotor plate set units cooperating with the stator plate sets, means connecting the axially alined shafts of all the rotor units for rotation in unison, said means including mechanism for mounting the rotor units insulated from each other and from said frame, and means for adjusting a rotor unit axially and radially to fix the spacing between and to match the contour of the plates of the same and a stator plate set.
16. A multiple variable air condenser comprising a supporting frame, a plurality of stator plate sets mounted on said frame, a plurality of independent coaxially arranged rotor plate set units cooperating with the stator plate sets, means connecting the axially alined shafts of all the rotor units for rotation in unison, said means including mechanism for mounting the rotor units insulated from each other and from said frame, and means for independently adjusting each of the rotor units with respect to its associated stator plate set both axially and radially.
17. A multiple variable air condenser comprising a supporting metallic frame, a plurality of stator plate sets conductively mounted on said frame, a plurality of rotor plate set units cooperating with the stator plate sets and provided with coaxially arranged shafts, means connecting the shafts of all the rotor units for rotation in unison, said means including mechanism for adjusting a rotor unit relative to its associated stator plate set and independently of the other rotor units.
18. A multiple variable air condenser comprising a supporting metallic frame, a plurality of stator plate sets conductively mounted on said frame, a plurality of rotor plate set units cooperating with the stator plate sets and provided with coaxially arranged shafts, means connecting the shafts of all the rotor units for rotation in unison, said means including mechanism for adjusting each of the rotor units axially independently of each other and relative to its associated stator plate set.
19. A multiple variable air condenser comprising a supporting frame, a plurality of stator plate sets mounted on said frame, a plurality of rotor plate set units cooperating with the stator plate sets and provided with coaxially arranged shafts, and means connecting the shafts of a pair of rotor units for rotation in unison, said means comprising a shaft intermediate the shafts of the rotor units, and means mounting the rotor shafts in said common shaft for independent adjustment therein.
20. A multiple variable air condenser comprising a supporting frame, a plurality of stator plate sets mounted on said frame, a plurality of rotor plate set units cooperating with the stator plate sets and provided with coaxially arranged shafts, and means connecting the shafts of a pair of rotor units.

units for rotation in unison, said means comprising a shaft intermediate the shafts of the rotor units, and means insulatably mounting the rotor shafts in said common shaft for independent adjustment therein.

21. A multiple variable air condenser comprising a supporting frame, a plurality of stator plate sets mounted on said frame, a plurality of rotor plate set units cooperating with the stator plate sets and provided with coaxially arranged shafts, and means connecting the shafts of a pair of rotor units for rotation in unison, said means comprising a shaft intermediate the shafts of the rotor units, rotor supporting members disposed laterally of said shafts and connecting the common shaft to the rotor shafts so as to support the latter at laterally spaced points and axially disposed rotor spacing members independently adjusted in said common shaft and engaging the rotor shafts for independently adjusting the rotor units axially with respect to the associated stator plate sets.

22. A multiple variable air condenser comprising a supporting frame, a plurality of stator plate sets mounted on said frame, a plurality of rotor plate set units cooperating with the stator plate sets and provided with coaxially arranged shafts, means for mounting each of the rotor units including mechanism for adjusting each of the rotor units axially to fix the spacing between the plates thereof and the plates of its associated stator and for adjusting the said rotor unit radially to match the contours of the rotor and

stator plates, said mounting means including a common shaft intermediate adjacent stator units.

23. A multiple variable air condenser comprising a supporting frame, a plurality of stator plate sets mounted on said frame and conductively integral therewith, a plurality of rotor plate set units cooperating with the stator plate sets and provided with coaxially arranged shafts, means connecting the rotor shafts for rotation in unison, said means including mechanism for mounting said rotor units insulated from said frame and from each other, and a shield plate arranged intermediate adjacent rotor units in conductive connection with said frame.

24. A multiple variable air condenser comprising a supporting frame, a plurality of stator plate sets mounted on said frame and conductively integral therewith, a plurality of rotor plate set units cooperating with the stator plate sets and provided with coaxially arranged shafts, means for connecting the rotor shafts for operation in unison, said means including mechanism for adjustably mounting each of said rotor units insulated from said frame and from each other, said mounting mechanism including a shield plate arranged intermediate adjacent rotor units in conductive connection with said frame.

Signed at New York city, in the county of New York and State of New York, this 1st day of July, A. D. 1926.

LESTER L. JONES.
